TAILOR'S SQUARE, AND METHOD FOR
DRAFTING PATTERNS

Valentino Ficcie, Tampa, Fla.

Substitute for abandoned application Serial No.
221,044, July 25, 1938. This application August
22, 1941, Serial No. 407,871

4 Claims. (Cl. 33—17)

This invention relates to devices for drafting patterns for men's garments and to a method of simplifying the designing of such patterns by reducing the number of measurements and computations necessary.

This application is filed as a substitute for application Serial No. 221,044, filed July 25, 1938, by the present applicant for the identical disclosure.

In modern tailoring practice, the general arrangement and manner of assembly of the pieces of cloth used for the various garments have been definitely determined by experience, and the exact lengths of certain dimensions are made proportional to certain standard bodily measurements, with the addition of certain allowances, as for seams, for bodily posture, and for departures from normal build.

The present system provides a system of transverse and longitudinal coordinate lines which may be directly determined from the various scales imprinted or otherwise formed upon the square herein described and illustrated, the graduations on such scales relating to certain measurements, as the girth of the chest, of the waist, and of the hips.

The system as applied to the coat patterns also provides for two fundamental lines, which in cooperation with each other and with the other coordinates, provide the necessary space for enlargement at the shoulder blades or for personal deformity, for corpulency and for over size, and they also determine the slope of the shoulder and the shape of the gorge.

It is an important object of the present invention to save time and to simplify the determination of the coordinate lines by placing the graduations at such locations upon the square that a single measurement will give both the proportionate length and the standard allowance.

In the drawings, Figure 1 is a plan view of one side of the square used in drafting coat and vest patterns; Fig. 2 is a plan view of the coordinate lines and the corresponding patterns of the pieces for the front and back of a coat; Fig. 3 is a plan view of the short arm of the square on twice the scale of Fig. 1; showing the portion used for determining the coordinates of pants patterns; Fig. 4 is a plan view of the coordinate lines and the corresponding patterns for the front and back pieces for a pair of pants; Fig. 5 is a plan view of a fragment of the long arm of the square on the same scale as that of Fig. 3, showing the portion used for laying out the coordinates for sleeve patterns; Fig. 6 is a plan view

of the coordinate lines and of the corresponding patterns for the sleeve of a coat; Fig. 7 is a diagram indicating the manner in which the graduations for the depth and width of the sleeve are determined; and Fig. 8 is a plan view of the coordinates and of the corresponding patterns for the front and back pieces of a vest.

The surface of the square shown in Fig. 1 is provided with a plurality of scales, each having 10 graduations or divisions numbered from 24 to 60. Each number on each of these scales refers to the breast measure. The manner of using the square and scales will first be described and their 15 location and manner of graduation will be explained later.

Drafting of the coat pattern

It will be observed that all of the scales on the surface of the square shown in Fig. 1 are 20 used for coat and vest patterns. Fig. 2 illustrates the patterns for the coat of a man of normal proportions and normal attitude, with a breast measure of 36 inches, waist measure of 32 inches, and seat measure of 38 inches.

Placing the square upon a sheet of pattern paper with the long arm across the paper and the short arm vertical, the line A—G is drawn substantially parallel with one side of the paper and the line A—N is drawn at right angles to the line A—G.

On the line A—G, the point B is marked opposite the graduation 36 on the "shoulder and gorge" scale; the point C opposite the graduation 36 on the "back notch" scale, and the point D opposite the graduation 36 on the "scye depth" scale. On the line A—N, the point H is marked opposite the graduation 36 on the "neck" scale, the point I opposite 36 on the "back" scale, the point L opposite 36 on the "scye" scale, the point M opposite 36 on the "shoulder point" scale, and the point N opposite 36 on the "full breast" scale. Sliding the square upon the sheet of pattern paper to the left to bring the corner to the point I, the point K is marked on the line A—N opposite the arrow designated "fundamental line," which is a distance of two inches to the left of point I.

Note that each graduation 36 refers to the 50 breast measure selected for the purpose of this description. The points E, F, and G are independent of the breast measure and are determined by the location of the waist line, at E, the seat or hip line, at F, and the bottom of the coat, at G, these measures being made directly with a tape measure and being dependent on the height

of the man for whom the coat is to be made, and upon the length desired for the bottom of the coat, which is a matter of style or preference.

Vertical lines are drawn downward from the points I, K, L, M, and N, and upward at points H and K, and horizontal lines are drawn to the left from points B, C, D, E, F, and G. A point O is located $\frac{3}{4}$ of an inch to the right and $\frac{3}{4}$ of an inch below the point b where the line drawn to the left from B intersects the line M—n drawn down from N. A straight line L—Z is drawn from the point L through the point O and a straight line is drawn from the point N to the point P where the line B—b intersects the line M—m drawn downward from M. The intersection of lines L—z and N—P is designated as p. A point Q is located at a distance of three inches above K on the vertical fundamental line K—k. A line from Q to A intersects the line drawn upward from H at R. The point S is at the intersection of line B—b and the fundamental line K—k. The point T is at the intersection of the lines L—l and D—d. Draw the lines C—T, M—S, and R—S. Note that the lines M—S and R—S give the slope of the shoulder.

The point U is at the intersection of the line C—T with the fundamental line K—k. Draw a horizontal line between the vertical lines I—i and K—k from U to u. Mark the point V at $\frac{3}{4}$ inch to the left of u and the point V' $\frac{1}{4}$ inch to the right of V; also mark a similar seam allowance of $\frac{1}{4}$ inch to the left of the point U. The point W is $\frac{3}{4}$ inch to the left of the point I' at the intersection of lines I—i and B—b. Mark point X on the line C—c $\frac{1}{4}$ inch to the left of line I—i. Mark point Y at the intersection of D—d and M—m. Mark the point Y' on the line L—l at a distance above T equal to T—Y. Mark point T' above T at one-third the distance to Y' for the scye notch where the sleeve seam comes in the scye. Mark the point Z at $\frac{1}{4}$ inches to the left of the point O on the line K—O extended. The line e—d—Z is drawn one inch to the left of the line N—n for the lap of a single-breasted coat. The point t is placed $\frac{1}{4}$ to the right of the point T to locate the top of the under arm dart.

It is believed that the method of determining the essential points of construction with relation to the established coordinate lines has now been made clear and that those familiar with the art can readily draft the pattern for the coat as indicated by the drawings.

Drafting of the pants pattern

As indicated in Fig. 3 the short arm of the square on the reverse side from that used for the coat and vest patterns is graduated for pants measure either waist or seat, with a double scale for width of legs.

A line 25—26 is first drawn lengthwise of a sheet of pattern paper, taking the distance from the point 25 to the point 26 equal to the length desired for the outside seam of the pants, and marking the point 27 at a distance from 25 equal to the length of the inside seam. Also mark a point 28 on the line 25—26 distant from 25 half the length of the inseam plus $1\frac{1}{2}$ inches.

Square lines across the paper from 26 to 29, 27 to 30, 28 to 31, and 25 to 32. Lay the square with the corner at 27 and the edge on the line 27—30, and mark point 33 opposite the graduation on the "waist and seat" scale corresponding to the seat measure of the person for whom the pants are to be made. Move the corner of

the square to the point 33 and mark point 34 on the line 27—30 opposite the graduation on the "crotch" scale corresponding to the seat measure. Square upward from the point 33 to the line

- 5 26—29, the distance 26—29 being equal to the distance 27—33. On the line 29—33, mark the point 35 at the same distance from 33 as 33 is from 34, the "crotch" distance. Draw the line 34—35 and connect its mid-point with the point 33. Mark point 37 at one-third of the distance from 36 to 33. Mark point 38 $\frac{3}{4}$ of an inch up from 35. Draw a curve substantially an arc of a circle through 38, 37, and 34. Mark point 39 $\frac{3}{4}$ of an inch to the right of point 33, and mark the point 40 $\frac{3}{4}$ of an inch to the right of point 34. Draw the line 29—39, and connect this line with the point 40 by an arc similar to the one through the points 38, 37, and 34. Mark point 41 to the left of 26 at a distance of $1\frac{1}{2}$ inches. 20 Mark point 42 midway between 27 and 34. Draw the vertical line 43—44 through the point 42 intersecting the line 28—31 at 45. The distance 27 to 42 is the same as the distance from 25 to 44.

Place the arrow of the "width of pants legs" 25 scales on the point 45 and measure points 46 and 47 on each side opposite the scale numerals corresponding to the width desired at the knees and similarly, with the same arrow on the point 44, mark the points 48 and 49 on each side opposite the scale numerals indicating the width desired at the bottom of the legs.

Draw a curve from 41 to 27 and substantially straight lines from 27 to 47 and from 47 to 49. Also draw a line from 49 to 46 and from 46 to 48 35 for one front piece, and for the other front piece, draw a curve from 34 to 46 tangent to the line 40—48. This gives the patterns for the two front pieces.

For the rear pieces, the pattern may be most 40 easily cut by placing a cut-out pattern for the larger front piece on another sheet of pattern paper and marking the lines 26—29, 27—30, 28—31, and 25—32 horizontally, and the lines 25—26 and 43—44 vertically. Mark point 50 one 45 inch to the right of point 27 and mark point 51 one-half inch to the right of point 47 and point 52 one-half inch to the right of point 49. Similarly, mark points 53 and 54 one-half inch to the left of points 48 and 46 respectively.

The curve through 37 and 34 is extended to point 55 which is measured from 34 a distance equal to half of the distance from 34 to 39 plus $\frac{1}{4}$ inch. Mark point 56 midway between points 29 and 43. Place the corner of the square at 56 and mark the point 57 opposite the graduation on the "waist and seat" scale corresponding with the waist measure. Point 58 is two inches to the right of point 57. A horizontal line to the right from point 30 intersects line 29—39 at 59. Connect 60 56 with 59.

Place the square with the outer edge of one leg on the line 56—59 and bring the outer edge of the other leg to the point 58. Draw the line 58—60. Square up from point 56 to point 60 and mark point 61 one-half inch below 60. Place one edge of the square on the line 58—60 and the edge of the other leg on the point 41. Draw the line 62—63 three inches down from 62 to 63. Mark point 64 $\frac{3}{4}$ inch to the left of point 62 on the line 58—60 and connect 63 with 64 to shape the dart. Draw the line 61—64. Draw a curve from 55 to 54 and straight lines from 58 to 50, 50 to 51, 51 to 52, 52 to 53, and 53 to 54, completing the draft for the rear piece.

Drafting the sleeve pattern

As shown in Fig. 5, the long arm of the square on the face opposite that used for the coat is graduated for sleeve proportions.

A sheet of pattern paper is folded in a straight line along its middle approximately parallel with the side edges. Laying the square on the paper with the chest measure graduation of the "sleeve width" scale at the line of fold of the paper, mark the point **1** at the corner of the square and draw the line **1—5** down parallel with the folded edge of the paper. Draw a second line from **6** on the folded edge to the point **1**. With the corner of the square still at point **1**, mark point **2** on the line **1—5** opposite the graduation on the "top of sleeve" scale representing the breast measure for the coat and point **3** opposite the corresponding graduation of the "sleeve depth" scale. With the corner of the square at **1**, mark point **7** midway between **1** and **6**, point **8** midway between **6** and **7**, and point **9** midway between **6** and **8**. Draw horizontal lines to the left from **2** and **3** and vertical lines downward from **6**, **7**, **8**, and **9**. Connect **2** and **7** and from the mid-point **10** of this line **2—7** draw line **10—11**, the distance **10, 11** being one-third of the length from **1** to **2**. Mark the point **12** where the line down from **8** intersects the line left from **2** and mark points **13** and **14** at distances $\frac{1}{4}$ of an inch above and to the left of **12**. Mark point **15** at $\frac{3}{4}$ of an inch to the left of point **2** and point **15'** at $\frac{1}{4}$ of an inch to the left of **15** or one inch from point **2**. Mark points **17** and **18** at $\frac{1}{2}$ inch to the right and below the point **16** where the line down from **8** intersects the line left from **3**. From the point **19** where the line down from **8** intersects the line left from **3**, measure downward to **20** a distance equal to that from **8** to **9**, one-eighth of the sleeve width.

Draw the upper curve through the points **2, 11, 7, 13**, and **14**, to **21**, and the lower curve through the points **15', 17, 18**, and **20** to point **21**. At **22**, where this curve intersects the line down from **9**, make a seam allowance of $\frac{1}{4}$ inch upward perpendicular to the curve, and from this point **22'**, draw a curve across to **20**.

From point **22**, measure downward to **23** a distance equal to the length desired for the sleeve inside. From the mid-point of line **22—23**, draw a line horizontally to the right to the line **1—5**, reaching it at **4**. At a distance of $1\frac{1}{2}$ inches below **23**, draw a horizontal line to the right to **5**.

Place the square with the breast measure graduation on the edge of the square in the "wrist" scale upon the vertical line **6—6'** and with the point of the arrow **w** on the line **5—6'** and move the graduation to the point **23**, the line **23'—24** forms the lower end of the sleeve. Connect **2** and **4**, and **15** and **4**, and draw a curve from **4** to **24**. Also draw the curves from **22** to **23** as arcs of circles each distant $\frac{3}{4}$ inch at their centers from the line **22—23**. When the pattern is unfolded, the portion for the outside of the sleeve extends outward to the points **22''** and **23''**, and the piece for the inside would lie with its corners at **15'', 22'', 23'', and 24''**.

Drafting the vest pattern

The coordinate lines for the vest are derived from the same side of the square and from the same scales as are those for the coat. The line **A—F** is first drawn approximately parallel with one side edge of a sheet of pattern paper and the line **A—N** is drawn at right angles to the first line, across the sheet.

The points **B, C**, and **D** are marked from the scales on the short arm and the points **H, I, L, M**, and **N** are marked from the five scales on the long arm of the square, exactly as was done with the correspondingly lettered lines and points in drafting the coat pattern. The fundamental line at **K** is located two inches to the left of **I** and the points **Q, R**, and **S** are found as previously set forth. The waist line **E—e** is the same as that for the coat, but the point **F** is three inches below the point **E**. The lines **M—S** and **R—S** determine the shoulder slopes. On the line **M—S** extended, the point **m** is placed $1\frac{1}{4}$ inches to the left of **M**.

At the mid-point of the line **D—d**, mark the point **a** and mark points **h** and **h'** each an inch to the right or left of the point **a**. Draw vertical lines down from **h** and **h'** to **j** and **j'** on the line **E—e**. Mark the point **o** half way between **E** and **j'** and the point **o'** half way between **e** and **j**. Mark point **d'** $\frac{1}{4}$ of an inch to the left of point **D**.

Place the arrow of the "vest waist" scale on the point **o** and mark points **p** and **p'** equally distant from **o** opposite the graduations corresponding with the waist measure. Similarly mark the points **q, q'**, on the right and left of the point **o'** at the same distances. Mark the point **e'** one inch to the left of **q'** and draw the line **d—e'—n'**. Connect the point **m** with **d** for a medium top opening or choose a higher or lower point for the style desired.

The tailor always measures the full vest length from the bone on the back of the neck, across the shoulder, and down to the point chosen for the bottom line of the vest. The point **A** will be at that neck bone in the finished garment, so that the distance **A** to **R**, plus the distance **m** to **d** is the top opening and the distance **A** to **R** plus the distance **m—d—e'—n'** is the full vest length plus an allowance of one inch for seams. From **n'** to **s** is $1\frac{1}{2}$ inches and from **n'** to **r** is 3 inches. Connect **r** and **s**. Draw the vertical lines **p'—f** and **q—g**. Mark points **t** and **t'** at a distance of $\frac{1}{2}$ inch to the right of **g** and to the left of **f** respectively.

Draw the curves from **h** through **q** to **t** on the line **F—g**, and from **h'** through **p'** to **t'**. Connect **s** and **t**. Also connect **t'** with a point **v** one inch above the line **F—f** and $\frac{1}{2}$ inch to the right of **p**. Mark a point **w** on the line **L—l** at a distance above **l** equal to the distance **M—L** or **m''—l**, and on the horizontal line **w—w'**, mark the point **w'** to the left of **w** a distance equal to one-third of the distance **m—l** plus $\frac{1}{2}$ an inch. On the line **M—S**, mark the point **m'** one inch to the left of the line **L—l**. On the line **L—l**, mark the point **l'** $\frac{1}{2}$ inch above the point **l**. Draw the scye curve from **m'** through **w'** and **l'** to **h**. On the line **I—i'**, mark point **l'** one inch above the point **i**. On the line **R—S**, mark the point **s'** one inch to the right of line **I—i**. Draw the rear curve from **s'** through **i'** to **h'**. Connect **A** with **C** and draw the line from **C** through **d'** and **p** to **v**, completing the draft.

Graduation of the scales

The graduations of the scales for the coat and vest are based upon the chest measure and the numerals refer to that measure except in the "vest waist" scale, which is based upon the waist measure.

On the short arm of the square, the graduation 24 on the "shoulder and gorge" scale is $1\frac{1}{2}$ inches from the corner of the square and the gradu-

tion 64 is four inches from the corner. It will be observed that $1\frac{1}{2}$ is one-sixteenth of 24 and 4 is one-sixteenth of 64. Each of the equal graduations of the scale thus represents one-sixteenth of the breast measure indicated by the numerals.

Each graduation of the "back notch" scale is at a distance from the corner equal to one-twelfth of the indicated breast measure plus a standard allowance of $1\frac{1}{8}$ inches.

The "scye depth" graduations are at a distance from the corner equal to one-sixth of the breast measure plus a standard allowance of $3\frac{1}{8}$ inches.

Along the edge of the square, the graduations are in inches, half-inches, quarter-inches, and eighth-inches.

On the long arm of the square, the graduations on the "neck" scale are at a distance from the corner equal to one-twelfth of the breast measure plus an allowance of $\frac{3}{8}$ of an inch.

On the "back" scale, the graduations are at a distance from the corner of one-sixth the breast measure plus $1\frac{1}{8}$ inches.

The "scye" scale distance is one-fourth of the breast measure plus an allowance of $5\frac{1}{2}$ inches.

The "shoulder point" graduation distance is one-third of the breast measure plus $5\frac{1}{2}$ inches.

The "full breast" graduation distance is one-half of the breast measure plus $4\frac{1}{2}$ inches.

The "vest waist" graduations are in two scales spaced equally on opposite sides of the arrow, each graduation being distant from the arrow one-eighth of the indicated waist measure.

On the other face of the square, the "crotch" scale is graduated to correspond with the seat measure, each graduation being at one-sixteenth of the seat measure from the corner.

The "waist and seat" scale graduation distance from the corner is one-fourth of the number of inches indicated by the numerals.

The "width of legs" scales have their graduations equally spaced on each side of the arrow at distances equal to one-fourth of the number of inches indicated by the numerals.

The "wrist" scale graduation distance is equal to one-eighth of the chest measure plus $1\frac{1}{4}$ inches.

The "sleeve width" scale is obtained by laying off a line 70—71, as shown in Fig. 7, on a slope such that the vertical height is to the horizontal distance as five is to twelve, or in other words, at an angle whose tangent is $\frac{5}{12}$. Since the square on the hypotenuse of a right triangle is equal to the sum of the squares on the other two sides, the hypotenuse will be thirteen in length when the base is twelve and the height five. On this line 70—71, a plurality of points 24a, 26a, 28a, etc., are laid off at distances from the point 70 equal to one-fourth of the distances in inches represented by the corresponding breast measures. These points are projected downward upon the horizontal base line to corresponding points 24b, 26b, 28b, etc. A point 72 is marked on the base line at one-half inch to the right of point 70. From this point 72, the distances to each of the points 24b, 26b, 28b, etc., are laid off on the square from the corner to give the graduation points 24, 26, 28, etc., of the "sleeve width" scale. The graduation distance from the corner is thus $\frac{3}{13}$ of the breast measure in inches expressed by the numerals upon the scale, minus one-half an inch.

The points 24a, 26a, etc., are projected horizontally upon the vertical line 70—73 to give a

series of points 24c, 26c, etc., each of which is $\frac{5}{52}$ of the breast measure corresponding to the numerals, above the base line. On the extension of the line 70—73 below the base line are marked the "top of sleeve" graduations, each distant from the point 70 one-twenty-fourth of the indicated breast measure plus a small allowance of one-eighth to one-fourth of an inch. The graduations on the "sleeve depth" scale are measured from the corner of the square at distances equal to the distances between points 24 and 24c, 26 and 26c, 28 and 28c, and so on. These graduation distances are thus $\frac{5}{52}$ of the breast measure, plus $\frac{1}{24}$ of the breast measure, plus a small allowance of one-eighth, three-sixteenth, or one-fourth inch, according to the looseness of fit desired.

The graduations on the scales of the square and the location of the coordinate lines and points established by its use are based upon the proportions of a man of normal build. A cutter familiar with the art will recognize the simplicity and efficiency of the system disclosed in the present method of drafting patterns as compared with previous systems, and he will observe that by the use of the allowances on certain scales, space is obtained on the paper for enlargements and modifications due to corpulency, deformity, or faulty posture, without the overlapping of patterns for the different pieces so frequently met with in other systems.

Since these modifications of the position of the points and lines are obtained by other measurements than those of the normal proportions established by the graduations of the scales of the square, they will be described in detail in the manual of instructions designed to accompany the square, but form no part of the description of the square itself.

I claim:

1. The method of preparing a coat pattern which consists in drawing upon a sheet of material a vertical side line and a horizontal top line, measuring on the vertical side line distances from its intersection with the top line, corresponding, with space allowances, to the shoulder and gorge depth, the back notch of the scye and the depth of the scye, measuring on the horizontal line distances from its intersection with the vertical side line corresponding, with space allowances, to the neck width, the back width; the scye front, the shoulder point, and the full breast measure, drawing vertical and horizontal coordinate lines from the points so measured, measuring a standard distance from the back width coordinate toward the scye front coordinate to determine a fundamental vertical line, measuring a point upon the fundamental line at a standard distance above the top line, connecting said point with the intersection of the top and side lines to determine by its intersection width the neck width coordinate the position of the top of the shoulder line, connecting the intersection of the fundamental line with the shoulder depth line to the top of the shoulder line and to the shoulder point measure on the top line to determine the slopes of the shoulder on the back and front pieces respectively, drawing the outlines of the pattern in agreement with the coordinates and cutting the sheet of material along the outlines.

2. In a method of preparing a pattern for a coat, the steps by which the slopes of the shoulder seams are determined, which comprise draw-

ing upon a sheet of material a side line and a top line at right angles thereto, drawing vertical coordinate lines parallel with the side line at distances therefrom equal to one-twelfth of the breast measure plus an allowance of three-eighths of an inch, one-sixth of the breast measure plus one and five-eighths inches, one-sixth of the breast measure plus three and five-eighths inches, one-fourth of the breast measure plus five and one-half inches, one-third of the breast measure plus five and one-half inches, and one-half of the breast measure plus four and one-half inches, drawing a horizontal coordinate line parallel with the top line at a distance therefrom equal to one-sixteenth of the breast measure, drawing a line from the meeting point of the top and side lines to a point three inches above the top line on the third vertical coordinate line from the side line and intersecting the first vertical coordinate line at a point above the top line, connecting this point of intersection with the point of intersection of the third vertical coordinate with the horizontal coordinate, and connecting this last-mentioned point of intersection with the point of intersection of the fifth vertical coordinate with the top line.

3. In a method of drafting a coat pattern as set forth in claim 2, the further step for deter-

mining the slope of the gorge which comprises connecting the point of intersection of the top line and the fourth vertical coordinate with a point lying three-quarters of an inch inward and three-quarters of an inch downward from the intersection of the sixth vertical coordinate and the horizontal coordinate.

4. The method of preparing a pattern for a coat for a person having a certain breast measure which comprises drawing upon a sheet of material a side line and a top line at right angles thereto, drawing coordinate lines parallel with the top line at distances therefrom equal to one-sixteenth of said breast measure, one-twelfth of the breast measure plus 1 and five-eighths inches, and one-sixth of the breast measure plus three and three-eighths inches, drawing coordinate lines parallel with the side line at distances therefrom equal to one-twelfth of the breast measure plus three-eighths of an inch, one-sixth of the breast measure plus one and five-eighths inches, one-sixth of the breast measure plus three and five-eighths inches, one-fourth of the breast measure plus five and one-half inches, one-third of the breast measure plus five and one-half inches, and one-half of the breast measure plus four and one-half inches.

VALENTINO FICCIO.
